UNITED STATES PATENT OFFICE.

PHILIP A. REUTTER, OF WATERBURY, CONNECTICUT, ASSIGNOR TO SCOVILL MANUFACTURING COMPANY, OF WATERBURY, CONNECTICUT, A CORPORATION OF CONNECTICUT.

PERFUME BOTTLE AND CAP.

Application filed January 30, 1925. Serial No. 5,683.

This invention relates to certain improvements in small containers and caps therefor, such as small bottles for containing perfume and the like.

5 The particular object of the invention is to provide a small bottle or vial and closing cap therefor, this cap being provided internally with means for engaging the bottle so as to be removably secured thereon both 10 to prevent loss of the caps in shipment and so that the caps will have a snug fit when the bottle is in use and prevent escape of the contents therefrom, the holding means being so formed as not to show from outside of the cap, so as to produce a cap of neat and attractive appearance, and at the same time permit ready removal and replacement of the cap.

15 It is a further object of the invention to produce such a construction that can be made cheaply and in which the holding means are formed on a member independent of the cap body, and concealed thereby.

20 With these and other objects not specifically referred to, the invention consists in certain novel parts, arrangements and combinations which will be described in connection with the accompanying drawings and the novel features pointed out in the claims 25 hereunto appended.

In the drawings,—

Figure 1 is a side view of the bottle and cap assembled;

Figure 2 is a central sectional view of Fig. 1 on an enlarged scale;

Figure 3 is a sectional view of the cap removed from the bottle;

Figure 4 is a sectional plan view of the cap taken on line 4—4 of Fig. 3, and

40 Figure 5 is a side view of the inner shell carrying the holding means.

Referring now to these drawings, the invention includes a cap which is provided with internally arranged engaging devices 45 for engaging with the neck of the bottle or vial, and in the best constructions these holding devices are such that they will frictionally and positively engage the cooperating part of the bottle. These holding devices will, furthermore, be of such character 50 that they will not show from the outside of the cap when the cap is on the vial, so that a bottle and cap of smooth finish and attractive finish will be produced.

55 In accordance with the invention, there

is provided a bottle marked 1, this bottle having a reduced neck 2, the upper edge of which is formed with a bead or lip 3, this bottle being made of glass or any other suitable or desirable material. A readily removable cap is provided for closing the bottle and this cap is frictionally and positively held in place on the bottle by the holding devices. While these holding devices may vary somewhat in construction, as illustrated, a cap 4 is provided with a closed end 5 which is inset in the body of the cap to form an upper shoulder 6. The holding devices are in the form of tongues 7, which may be conveniently produced by slitting, as indicated at 8, the upper portion of the walls of a shell 9. A sufficient number of these tongues are provided to effect the required engagement of the cap with the body neck. The lower portion of the shell 75 is unslotted to form a flange 10.

This shell is secured in the cap body in any suitable manner. A convenient way of doing this is that shown, in which the upper edge of the shell bears against the inner surface of the shoulder 6 and the bottom of the cap body is inturned, as shown at 11, against the bottom of the flange 10, so that the shell is rigidly held in place in the cap. This shell is formed of light spring metal 80 so that the tongues are resilient or springy and thus afford a good frictional engagement with the bottle neck.

In the best constructions the tongues are also engaged positively with a cooperating part on the bottle neck so that both a frictional and positive engagement is effected.

This engagement, however, will be such that the cap may be readily removed from and replaced in position on the bottle. In the particular construction illustrated, the upper ends of the tongues are bent or turned to form a shallow groove 12 which will slip over the lip or bead 3 on the bottle neck and will act to grip this bead so that the cap will be securely held in position. Due to the shape of the bead and groove and the spring of the tongues, the cap can be readily removed from and secured into position on the bottle without deforming or injuring the cap.

With the construction shown and described a very simple and effective cap and bottle is produced without the use of screw threads, indentations or other devices which

would show from the outside of the cap, and the cap can be made of very light and consequently cheap material.

While the cap and bottle shown are preferred, it will be understood that some changes and variations may be made in the form and positioning of the holding devices without departing from the invention as defined in the claims hereunto annexed.

19. What I claim is:

1. A bottle or vial having a mouth and a removable and replaceable closing cap therefor, a shell inside the cap, complementary engaging lip and groove devices on the 15 bottle and shell for permitting bodily removal and replacement of the cap and shell on the bottle, and means for securing the shell in the cap.

2. A bottle or vial having a mouth formed 20 with a lip and a removable and replaceable closing cap, a shell in the cap slitted to form spring tongues and removable from the bottle with the cap, the ends of the tongues being formed to embrace the lip, and means for 25 holding the shell in the cap.

3. A bottle or vial having a mouth and a removable and replaceable closing cap therefor, said cap being formed with a shoulder, and a shell in the cap removable from the

bottle with the cap and formed with inwardly extending holding tongues, the shell abutting against the shoulder and being held in place by inturning the end of the cap.

4. A bottle or vial having a mouth formed 35 with a rounded lip, a removable and replaceable closing cap, a shell in the cap, spring tongues on the shell provided with grooves for removably engaging the lip, and means for holding the shell in the cap. 40

5. A bottle or vial having a mouth formed with a rounded lip, a cap, and spring tongues located inside the cap and having grooves for removably engaging the lip.

6. A bottle or vial having a mouth and a 45 removable and replaceable closing cap therefor, said cap being formed with an upper shoulder, and a shell in the cap removable from the bottle with the cap and slit to form upwardly extending holding tongues 50 rising from a flange, the shell abutting against the shoulder and the lower edge of the cap being inturned under the flange of the shell.

In testimony whereof, I have hereunto set 55 my hand.

PHILIP A. REUTTER.
